UNITED STATES PATENT OFFICE.

JAMES C. GAFFNEY, OF NEW YORK, N. Y., ASSIGNOR TO DEMOCRACY PLAYING CARD COMPANY, INCORPORATED, A CORPORATION OF DELAWARE.

DESIGN FOR A PLAYING-CARD.

54,612.

Specification for Design.

Patented Mar. 9, 1920.

Application filed June 16, 1919. Serial No. 304,703. Term of patent 7 years.

To all whom it may concern:

Be it known that I, JAMES C. GAFFNEY, a citizen of the United States, residing in the city and county of New York, State of New York, have invented a new, original, and ornamental Design for a Playing-Card, of which the following is a specification, reference being had to the accompanying drawing, forming part thereof.

The figure is a face view of a playing card, showing my new design.

I claim:

The ornamental design for a playing card, as shown.

In testimony whereof I have signed this specification in the presence of two subscribing witnesses.

JAMES C. GAFFNEY.

Witnesses:

R. B. CAVANAGH,
M. H. GEBHARDT.
